UNITED STATES PATENT OFFICE.

WILLIAM H. HANLON, OF MARTINEZ, CALIFORNIA.

TYPESETTING MACHINE.

Application filed April 24, 1919, Serial No. 292,424. Renewed December 4, 1922.

To all whom it may concern:

Be it known that I, WILLIAM H. HANLON, a citizen of the United States, residing at Martinez, in the county of Contra Costa 5 and State of California, have invented certain new and useful Improvements in Type-setting Machines, of which the following is a specification.

My invention relates to a machine to set 10 and distribute printing type which is operable by keys in a manner simulating the operation of a typewriter thus accomplishing the result of moving the type rapidly and entirely mechanically both in the setting and 15 distributing thereof and practically as rapidly as a typewriting machine is operated, whereby the onhand supply of type may be greatly reduced since a form may be rapidly set up and distributed and where- 20 by the cost of the printing may be reduced in view of the reduction in time and whereby printing may be effected in a much shorter period of time.

In carrying out the invention, I aim to 25 provide type containers; keys to set or dis- tribute type and which are movable relative to the containers so as to be capable of sup- 30 plying capital as well as small type; means operated by depression of the keys to set or dis- 35 tribute type; a particular form of clasp means for the type and a spreader associated with the clasp means; means to dislodge the type from the clasp during the setting 40 operation but capable of movement to a non- interfering position, optionally; means op- 45 erable to return type to the clasp during the distributing operation, and the various sub- mechanisms and details of construction which will be hereinafter described in con- 50 nection with accompanying drawings illus- trating one preferred embodiment.

In said drawings:-

Figure 1 is a diagrammatic front elevation, partly broken away, illustrating my 55 improved mechanism;

Figure 2 is a fragmentary longitudinal 60 sectional view thereof;

Figure 3 is a cross sectional view on the 65 line 3—3 of Figure 5;

Figure 4 is a cross sectional view on the 50 line 4—4 of Figure 2;

Figure 5 is a fragmentary front elevation 60 of the printing drum and attached parts;

Figure 6 is a fragmentary plan view of 65 the parts of Figure 5 and associated parts;

Figure 7 is a cross sectional view on the 70 line 7—7 of Figure 5;

Figure 8 is a cross sectional view on the 75 line 8—8 of Figure 7;

Figure 9 is a fragmentary plan view of the 80 printing drum and the turnable type dis- tributing means;

Figure 10 is a side elevation of the turn- 85 able type distributing member;

Figure 11 is a fragmentary front elevation 90 of one of the type carrying clasps and type holder associated therewith;

Figure 12 is a plan view of one of the 95 type holders;

Figure 13 is a cross sectional view on the 100 line 13—13 of Figure 2;

Figure 14 is a view of the parts of Fig. 13 but with the clasp in engagement with a 105 type;

Figure 15 is a cross sectional view on the 110 line 15—15 of Fig. 3;

Figure 16 is a cross sectional view on the 115 line 16—16 of Figure 3, and

Figure 17 is a detail perspective view of 120 one form of type with which the apparatus 125 co-operates.

Referring specifically to the drawings, a main casting or frame A adapted to be sup- 130 ported in any suitable manner, is provided, 135 preferably having an upright rear wall 18 in which a shaft 19 is journaled. The shaft passes loosely through a wall or head 20, rigid with the base, and has a printing drum B fixed thereon to turn therewith, but pref- 140 erably being detachable from the shaft, 145 although its particular construction forms no part of the present invention.

The type T which may be of the general 150 shape shown by way of example in Fig. 17, 155 is held in tubes or containers C. These containers are of such size as to accommodate 160 two rows of the type as shown in Figure 12.

As shown in Figs. 1, and 2 a bar 21 ex-

tends under and transversely of the base, being fastened in place by bolts 22 depending from the base A and by bars 23 suspended from said base and secured to the base and bar 21, respectively, by means of screws 24 and 25. A suitable number of rods or pins 26 are rigidly mounted by the bar 21, terminating below the tubes C and each being surrounded by a coil expansion spring 27 which extends into the tube above it so as to urge the type therein upwardly into contact with L-shaped retainer leaves 28. In the base A, a suitable number of slots 29 are provided through which the tubes or containers C extend for movement toward and away from the printing drum, being normally held in a position farthest from the drum by means of retractile coil springs 30 secured to the containers and to the base as shown. Plates 31 and 32, carried by the tubes, respectively overlap and underlap the base to maintain the containers in proper position. The type are adapted to be engaged by clasps generally designated D. When the containers are in their normal position, the type T of the row nearest the drum B, being the right hand row in Figures 2 and 12, are to be engaged by the clasps and these type are preferably of the small letter class. The other row contains type of the capital letter class and in order to bring these rows beneath the clasps, the containers have been slidably mounted as previously described. In order to slide the containers, which move as a unit in view of their connection together by means of the plates 31 and 32, a key 33 is depressed. This key is carried by a lever 34, pivoted as at 35 to a post 36 rising from the base. On one of the containers (see Fig. 2) an abutment 37 is provided which is engaged by a cam end 38 of said lever 34 which forces the containers to the rear of the slots 29. A spring 39 fastened to the lever 34 and to a front raised wall 40 of the base restores the lever 34 to and maintains it normally in a retracted position as in Figure 2.

Attention is called to the fact that in the drawings particularly Fig. 1, as many containers C as will be used in actual practice have not been shown since it might tend to obscure the disclosure. Also, some of the tubes or containers C are curved as at 41 in order to co-operate with the arrangement of the clasps D, the type fitting the containers relatively loose and the curvature thus affording no interference to the movement of the type upwardly in the containers and to the action of the springs therein.

Referring more specifically to the retainer leaves 28, it will be noticed that they are riveted or otherwise fastened at 42 to the tubes C and that their free or horizontal arm but slightly overlaps the type. Lugs 43 project inwardly from said horizontal arms.

Said clasps C, while they may be of any suitable construction, preferably have grasping arms 44, extending from resilient arms 45 tensioned to move the grasping arms together. Arms 45 bifurcate from type-carrier arms 46, one for each clasp, pivoted at 47 to a suitable part of the base A, and which is normally urged downwardly by a spring 48 connected to arm 46 and said base. The inner ends of the arms 46 are formed to provide hooks 49. The different pairs of resilient arms 45 are held separated by means of a wedge or detent 50, which extends therebetween so as to normally maintain the grasping arms 44 separated or spaced as in Figs. 4, 11 and 13. The wedges 50 have laterally extending lugs integral therewith at 51 to support the resilient arms 45, thus limiting their downward movement and preventing separation of the grasping arms beyond a predetermined degree. As best shown in Figs. 2 and 4, the wedges and lugs are integral parts of rods 52 guidingly mounted through eyelets 52' fastened to the rear of the containers C, and pivoted as at 53 to levers 54. Levers 54 are pivoted at 55 to the base and are depressible at their front ends by means of keys 56. Also these levers 54 are normally held in their raised position by means of spring 57. Their downward movement is cushioned in any suitable manner, as by means of a rubber buffer bar 58 held by a container 59 mounted on the base. Adjacent to each lever 54, a link 60 is pivoted at 61 to the base. Each link has an elongated angularly disposed slot 62 into which a laterally extending pin 63 carried by the adjacent lever 54 extends. At the upper end of each link 60, a pin 64 extends laterally into the slot of the hook 49 of the adjacent type carrier arm, being normally located above the base of said slot.

In setting small letter type or distributing them, the keys 56 corresponding to the letters are depressed while if capital letter type are to be set or distributed, the shift key 33 is first depressed and thereafter the keys, corresponding to the letters are depressed. As levers 54 move downwardly under urgency of the keys 56, rods 52 move correspondingly and the springs 48 pull the levers 46 downwardly so that the clasps D will engage the type. Pressure on any one of the keys 56 causes pin 64 on arm 60 to move in the arc of a circle about pivot 61 and leftward and slightly downward from its position in Figure 2. As the clasps move downwardly, the arms 44 while still spread, at their beveled edges 65, engage and extend between the lugs 43, forcing the leaves 28 outwardly, as in Fig. 14, and then extend on opposite sides of the uppermost type member as shown also in that figure, after which the wedge 50 moves completely from between the arms 44, permitting the

latter to flex together by the inherent resiliency of the arm 45, so that the type is clasped. During this phase of movement, the arms 45 are held against the lugs 51 by the spring 48 until the type carrying arms are on the opposite sides of the type. It is to be understood that the springs 28 are of very thin metal or other material so as not to offer such a degree of friction or resistance as will hold the clasp or in any manner interfere with their operation. When the levers 46 reach the position described, pins 64 of links 60, which have been moving in the arc 10 of a circle by levers 54, due to pivotal movement from pins 61 and the pin and slot connection at 63, reach the base of the slot of hook 49 whereupon the pins 64 strike the hooks 49, throwing the levers into the dotted line position shown in Figure 2 to set or distribute the type with the aid of mechanism hereinafter described. It may be mentioned that as the levers 54 and 46 are restored to normal position by means of their springs 25 57 and 48, respectively, the wedges 50 separate the arms 45 so that type which they may contain for distribution and which are removed from the printing drum as herein-described, may fall from the clasp arms 30 44, directly into the tubes or containers C. Previous to this distribution, the leaves 28 may be swung from the rivets 42 as pivots to a position where they will not extend over the containers, as suggested by the dotted lines in Figure 12 and also the springs 35 27 may be removed or in any approved manner be held depressed and inactive.

In the path of movement of the key bars 46 is a plunger rod 66 (Figs. 3, 5, 7, and 16) 40 which is slidably mounted in the head 20, has a head 67, is rectangular in cross section to prevent rotation, is normally projected outwardly by means of a spring 68 fastened to the rod and to the head and the movement 45 of which is limited by means of a pin 69. Rod 66 may have gear teeth 70 thereon adapted to mesh with those of a pinion 71 fixed on a shaft 72 mounted for rotation and vertical sliding movement in the head 20. The 50 rod operates a turnable distributor E later to be specifically described and may be held in a lowermost or inactive position through the engagement of a manually operable cam 73 against a detent 74 having an eye 75 through 55 which shaft 72 passes and which has pins 76 between which the eye 75 is disposed. See Figs. 3, 5 and 15. A bracket 77 is pivoted on the head 20 at 78 which is capable of assuming either the full line or dotted line 60 position of Fig. 5. In the head 20, a plurality of recesses 79 and 80 are provided to selectively receive a pin 81 to secure the bracket 77 in the dotted line and full line positions of Fig. 5. See also Fig. 8. Said pin 81 65 has a head 82 and is slidably mounted in a

housing 83. In the housing, a spring 84 surrounds pin 81 and bears against the end wall thereof and an abutment plate 85 on the pin so as to normally urge the pin inwardly, When the bracket is moved from one position to another, the pin is simply moved outwardly to disengage the recesses, whereupon the bracket is swung on the pivot to the desired position and the pin released so as to move into the proper recess. Arms 86 70 extend outwardly from the bracket and rotatably mount a rod 87 which has a horizontal arm 88 and a vertical ejector arm or crank 89. A spring 90 surrounds the rod, having one end connected to the arm 88 and the other end fastened to the uppermost arm 86 at a lug 91 thereof. This spring holds the ejector device in its outermost position, which is the full line position of Fig. 6. The rod 87 is held against downward displacement by means of a pin 92 resting on the lowermost arm 86. A pinion 93 is keyed to the rod 87. An angle arm 94 is rigid with rod 66 and is connected to a rack or gear arm 95 which is slidably mounted in the head 20 90 and has a pin 96 to engage the interior wall of the head 20 for limitation of its movement.

As the levers 46 move upwardly toward the printing drum they strike the head 67, 95 moving the rod 66 inwardly and accordingly sliding the rack bar or arm 95 resulting in the turning of pinion 93 and accordingly of the shaft 87 so that the arm 89 will move from the full line position of Fig. 6 into the dotted line position of the same figure to eject the type from the clasp by moving against it and the impact throwing it, as in Fig. 6, into the opposite groove or between the adjacent rails 100 of the 105 printing drum, it being understood that this drum is rotatable by any suitable means to register the desired groove of the printing drum with the point of delivery of the type. After the type reach the printing drum, 110 they are fastened or held therein in any suitable way against displacement. It may be mentioned that the drum is diagrammatic of that used on a "multigraph" printing machine and that the type are of the usual 115 general shape for use with that machine.

Preparatory for the distributing operation after the drum or form has effected the printing, the bracket 77 is swung to the dotted line position of Fig. 5 so that the 120 ejector 89 will not be in the path of movement of the levers 46. Thereupon the cam 73 is swung on its pivot to disengage detent 74. There is sufficient clearance provided in the head 20 to permit the shaft 72 to 125 move upwardly into the dotted line position of Fig. 3 under the urgency of a spring 101 to bring the pinion 71 into engagement with the teeth 70 and to project the distributing head E above the periphery of the head 20. 130

Thus, should the levers 46 now move upwardly, their engagement with bar 66 at head 67 will turn pinion 71 moving the head E in an arc of 180°. Head E is normally disposed in a recess 102 which also houses the spring 101 and which spring is expansive and bears against the under surface of head E and rests on the base wall of the recess 102. When head E is raised or projected, 10 its normal position is as shown in Fig. 9 namely with a type-receiving groove 103 in registry with the uppermost groove of the printing drum. When distributing the type, removable or other coil spring 104 15 (Fig. #3) may be used, being insertible into the grooves of the drum, and urging the type toward and one at a time into said groove 103. The type enter the groove 103 against the tension of ejector springs 105 and the 20 lateral extensions at the base of the type enter the enlargements of the grooves 106, limiting the head to reception of but one type at a time. With a type thus urged into the groove 103 by the spring, lever 46 is 25 raised by depressing its key, in order to receive and return or distribute the type to the containers, such lever will strike the head 67, forcing the rod 66 inwardly causing the teeth 70 to turn the pinion 71 and accordingly the rod 72 and head E with a type 30 therein 180° when the groove 103 of the head will be opposite the clasp of the active lever 46 and spring 105 will expand and throw the type into friction tight relation with and 35 between the arms 44. After obtaining the type, levers 46 will be pulled back to normal position by springs 48 and in moving to this position wedge 50 moves between the arms 44, separating them and permitting the type 40 to drop into the container beneath. A broken rim 107 may form part of head 20 and surround the head E to prevent ejection of the type while head E is turning.

Since merely the preferred embodiment 45 has been illustrated and described, it is to be understood that changes in the details of construction, arrangement and combination of the parts may be made without departing from the spirit and scope.

50 I claim:—

1. In printing mechanism, upwardly movable means operable to set type, means to contain two rows of type, means to move the last mentioned means for co-operation 55 of the type of either row and at the top thereof with the first mentioned means.

2. In printing mechanism, a type carrier, 60 depressible means to actuate the carrier to set type, and means to initially move the carrier in the opposite direction during a second operation to engage the type.

3. In printing mechanism, a type carrier, 65 said carrier having a type engaging means, means depressible to operate the carrier, and means associated with the depressible

means to normally maintain the second mentioned means in a receiving position and spaced from the type.

4. In printing mechanism, a type clasp, 70 having arms movable toward each other, means to operate the carrier, and means movable with the last mentioned means to normally maintain said arms in separated relation.

5. In printing mechanism, a type carrier 75 having a clasp provided with arms movable relatively, means to normally maintain the arms in separated relation, means to move the last mentioned means relatively to the arms and means operable during said 80 movement to cause the arms to grasp the type.

6. In printing mechanism, a form, a carrier for type, means to operate the carrier toward the form, and means to move the 85 carrier into grasping relation with the type prior to movement toward said form during each setting operation.

7. In printing mechanism, a lever having 90 a clasp with relatively movable arms to grasp type, a second lever means to spread the arms of the first lever carried by the second lever, and means independent of the second lever to operate the first lever during movement of the second mentioned 95 means.

8. In printing mechanism, a type carrier, means normally preventing movement of the carrier toward the type, mechanism operable to move said means away from the 100 type carrier and thereafter toward the printing form and means operable to draw the carrier into grasping relation with type before movement toward the form.

9. In printing mechanism a carrier for 105 type, means normally preventing movement of the carrier toward the type, a spring urging the carrier toward the type, said carrier having an enlarged slot, an operating lever to which the first mentioned means is 110 connected and means to operate the type carrier through movement of the second mentioned lever including means extending into said slot and disposed normally above the base thereof.

10. In printing mechanism, a lever, a type carrier having a clasp provided with relatively movable arms, a wedge member for 120 said arms pivoted to the lever, a spring to normally draw the carrier toward the type, said carrier having an enlarged slot, a link movable through movement of the lever, and said link having means extending into the slot and disposed normally above the base thereof.

11. In printing mechanism, a base, said base having a slot therein, a container disposed in said slot adapted to hold type, means mounted by the base operable to slide the container, return spring means asso- 130

ciated with the container, plate means carried by the container and co-operating with the base, and type carrier means co-operating with the container and mounted from the base.

12. In printing mechanism, a container in which type are disposed, means to retain type, carrier means for the type engageable with the said means to displace the same to permit removal of the type and means to urge the type toward the retaining means.

13. In printing mechanism, a type container, a spring retainer for the type, and a clasp for the type engageable with said spring to move it out of retaining relation.

14. In printing mechanism, a type container, a laterally movable retainer for the type, a carrier for the type, said carrier having a clasp provided with arms, said arms being engageable with the retainer prior to a grasping operation, and means to hold the arms separated while engaging said retainer and moving into clasping relation with the type.

15. In printing mechanism, a type container for the type, means to urge the type upwardly, retainer means for the type, a carrier for the type, and a clasp associated with the carrier to displace said retainer prior to engagement of the clasp with the type.

16. In printing mechanism, a type container, a retainer for the type, a carrier for the type, said carrier co-operating with the retainer for setting of the type, and said retainer being movable out of the path of the carrier to permit distribution of the type.

17. In printing mechanism a form, means to carry type to the form, and means operable through movement of said means to remove type from said means.

18. In printing mechanism, a form, a carrier to convey type to the form, and means operable through movement of the carrier to eject type from the carrier.

19. In printing mechanism, a carrier to convey type, means movable by the carrier, and means to eject type from the carrier, operable by the first mentioned means.

20. In printing mechanism, a carrier for type, means movable in substantially the same general direction as the carrier to eject type from the carrier, and gearing mechanism to drive with said means operable through movement of the carrier.

21. In printing mechanism, a carrier for type, a plunger in the path of movement of the carrier having a gear member, a gear member in mesh with said gear member, and a type ejector rigid with the second gear member.

22. In printing mechanism, a carrier for type, a plunger in the path of movement of the carrier having a gear member, a gear

member in mesh with said gear member, a type ejector rigid with the second gear member, and a return spring means associated with the type ejector.

23. In printing mechanism, a type carrier, a plunger operable by said type carrier, and an ejector for the type movable by the plunger into and out of operative relation with the carrier.

24. In printing mechanism a type carrier, a plunger operable by said type carrier, a bracket, movable into and out of operative relation with the carrier, an ejector for the type, pivotally mounted by the bracket, a gear on the ejector, gear means meshing with the gear and carried by the carrier and a return spring means associated with the ejector and bracket.

25. In printing mechanism means to convey type, ejector means associated with said means, and means to selectively secure the ejector means in the path of movement of the first mentioned means for operation or out of the path of movement of said means.

26. In printing mechanism a base member, a type carrier, an ejector for the type having a bracket, member, and means to secure said ejector in an operative and in an inoperative position comprising openings in one of said members, and means on the other of said members to extend into said openings.

27. In printing mechanism, means to receive type, and means operable to receive type therefrom for distribution and means on the last mentioned means to discharge type therefrom.

28. In printing mechanism a head to receive type, means to receive type from said head, and means to move the head into operative relation with the first means and means carried by the head to discharge type therefrom.

29. In printing mechanism in combination with a form holding a plurality of type, a head to receive said type, means to limit reception of a predetermined quantity of type by the head, and means carried by the head to discharge type therefrom.

30. In printing mechanism, a head having a type receiving opening, means to feed type therein, a spring extending into said opening compressible by type therein, means to move the head with the spring compressed, and means to receive the type under urgency of the spring after movement of the head.

31. In printing mechanism a type distributing member, said member being depressible, means to urge the member upwardly, a plunger to operate the member, and means co-operating the plunger to maintain the member depressed.

32. In printing mechanism a plunger pro-

vided with gear teeth, a slidable and rotatable shaft, a gear on said shaft, to mesh with said teeth, a distributing head carried by said shaft, a spring to urge said head and shaft upwardly, means operable to depress the shaft, and a member co-operating with said means to maintain the shaft depressed.

33. In printing mechanism a distributing head, a spring in said head, means to urge 10 type into said head, said type compressing

said spring, means to maintain the type and spring in such relation during a part of the movement of the head, and said spring thereafter ejecting the type.

In testimony whereof I affix my signature 15 in presence of two witnesses.

WILLIAM H. HANLON.
